UNITED STATES PATENT OFFICE.

GEORGE R. MCCHESNEY, OF NEW YORK, N. Y.

SASH-FASTENER.

SPECIFICATION forming part of Letters Patent No. 631,964, dated August 29, 1899.

Application filed November 30, 1898. Serial No. 697,876. (No model.)

To all whom it may concern:

Be it known that I, GEORGE R. MCCHESNEY, a citizen of the United States, residing at New York, in the county of New York and State of New York, have invented new and useful improvements in Sash-Fasteners, of which the following is a specification.

My invention relates to an improvement in sash-fasteners.

10 It is an object of my invention to provide an improved sash-lock which shall operate to lock the upper and lower sashes in any required adjusted positions and which may be readily manipulated to unlock the same, said 15 lock operating simultaneously on both sashes to lock or unlock them.

My invention has for a further object the provision of improved mechanism for operating the lock, which mechanism may be set 20 to hold the lock in a locked or unlocked position.

The above are the general objects of the invention. Further objects of the invention relate to certain details of construction and 25 operation of the parts, all of which will more clearly hereinafter appear.

In the accompanying drawings, illustrating the invention, Figure 1 is a sectional elevation. Fig. 2 is a horizontal section. Fig. 3 30 is a sectional elevation taken at right angles to Fig. 1. Fig. 4 is a perspective view of the lock and the operating mechanism therefor. Fig. 5 is an inside view of the lock, and Fig. 6 is a sectional detail view of the operating 35 mechanism.

The reference-numerals 1 and 2 indicate, respectively, the upper and lower window-sashes, and 3 indicates the window-sash frame. Secured along the inside face of one 40 of the outer rails of sash 1 and extending from top to bottom thereof is what I term a "locking-strip" 4, which lies flush with the surface of the rail and is provided at equal intervals with a series of oblong apertures 5.

45 A similar strip 6 is provided along the outside face of the corresponding rail of the lower sash. Secured in the frame 3 at a height corresponding to that at which the horizontal rails of the window-sashes meet is 50 the locking mechanism, the casing of which is indicated by the numeral 7. Said casing is made from a single piece of metal having

its edges turned inward at right angles to its body portion to afford flanges inclosing the mechanism in the ordinary manner and is secured in any preferred manner within the frame to lie flush with the surface thereof. 55

The main locking member comprises a lever-arm 8, having at one end upper and lower integral extensions 9 10, forming what I term 60 a "locking-arm," and at said end being loosely mounted on a stud 11, secured to the casing 7 and being adapted to slide on said stud, as hereinafter described. Secured on the end of the stud 11 within the casing is a leaf-spring 12, which bears at opposite ends on the extensions 9 10 toward the ends thereof, as shown. Said extensions 9 10 have on opposite sides integral portions 13 14, respectively, bent at right angles to said extensions 65 and projecting through suitably-shaped openings 15 16, formed in the face of the casing. The upper projecting portion 13 has on its upper side an integral portion 17, bent at right angles to itself and curved downwardly, 70 forming what I will term a "bearing-flange," which projects a considerable distance from the face of the casing and bears against the edge of the upper window-sash, as shown and for a purpose presently described. The casing 7 is suitably cut out to receive said bearing-flange 17, as shown. The end of the projecting portion 13 is also bent outward at right angles to said projecting portion and in the same direction as the bearing-flange 17 to 75 form a locking-hook 18, which also is curved slightly downward, as shown, and is adapted 80 to engage in the apertures 5 of locking-strip 4. The lower projecting portion 14 has a corresponding bearing-flange 19 and locking-hook 20, these parts being curved upwardly 85 and extending in an opposite direction to the upper bearing-flange and hook and being designed to engage, respectively, with the lower sash and locking-strip 6 in the same manner 90 as the like parts just described. The hooks 18 and 20 being located, respectively, on opposite sides of an integral swinging arm formed by the extensions 9 and 10 will be moved simultaneously in opposite directions 95 when the lever-arm 8 is raised or lowered, as will be understood.

Mounted on a stud 21 is a coiled spring 22, having one end bearing against a flange 23

of the casing and its other end suitably bent and provided with a friction-roller 24, bearing upward against the under side of the lever-arm 8. The spring 22 tends to hold the lever-arm 8 in a raised position, and thus keeps the locking-hooks 18 and 20 in engagement with the apertures of their respective locking-strips.

The free end of lever-arm 8 is provided with a series of apertures 25, in any one of which, for the purpose of adjustment, may be secured the upper end of the rod 26 for operating said lever-arm.

Those portions of the casing 7 which are cut away to provide the openings 15 16, respectively, are turned outward at right angles to said casing on opposite sides of a vertical line, in such manner that they may engage opposite sides of the parting-strip 27, in which they may be seated to lie flush with the respective faces thereof, said bent portions being indicated, respectively, by the numerals 28 and 29. The sides of the parting-strip respectively opposite the bent portions 28 and 29 are cut out to form recesses 30 and 31 to permit movement of the locking-hooks.

The rod 26 extends downward through an opening 32 in flange 23 and is connected to the operating mechanism, which will now be described.

The frame 3 is suitably recessed to receive a hollow cylindrical housing 33, provided at its inner end with a circular flange 34, having apertures therein whereby the housing may be secured by screws or the like to the window-frame. The cylindrical housing is provided with two longitudinal slots 35 36, respectively, connected toward their outer ends by a cross-slot 37. Extending through the housing 33 and revolvably seated therein is a plunger 38, having secured therein a pin 39, which is adapted to work in the slots 35, 36, and 37. Encircling the plunger 38 is a coiled spring 40, which bears at one end against the end of the housing and at its other against a shoulder 41, formed on the plunger. The spring 40 tends to press the plunger 38 outward or toward the operator. Said plunger, as stated, extends through the housing, its outer end having a milled turned button 42 of any preferred kind and its inner portion without the housing being continued as a squared extension 43, which projects some distance within the frame. On this squared portion is secured by means of a set-screw 44 a crank-arm 45, which may be adjusted longitudinally on said plunger and secured by said set-screw. Said crank-arm is of the curved shape shown and is bifurcated and provided with a series of transverse apertures 46, adapted to receive a pin by means of which one end of a link 47 may be secured in the bifurcation of the crank-arm. Said link is provided at each end with a series of perforations 48 49, respectively, the series 49 being intended for the pin securing said link in the crank-arm and the series 48 being intend-

ed for the lower end of rod 26. By means of these perforations in the crank-arm and link the correct adjustment may be obtained relative to the length of the rod 26 to insure that a throw of the crank-arm shall lock or unlock the sashes, as the case may be. It will be understood without further specification that recesses, such as shown at 50 and 51, will be provided in the frame and of such dimensions and so located as to permit the proper working of the parts described. The parts are normally in the locked position shown.

The operation is as follows: When it is desired to unlock the sashes, the plunger 38 is pushed inward against the resistance of spring 40, which brings the pin 39 opposite the slot 37. The turn-button 42 is now turned downward, which brings pin 39 opposite slot 36, when the spring 40 will throw the plunger outward, the pin 39 entering slot 36. As the plunger 38 is turned downward the crank-arm 45 is turned with it, and this movement, through the medium of link 47 and rod 26, pulls the lever-arm 8 downward against the resistance of its spring 22, whereby the locking-hooks 18 and 20 will be drawn out of the apertures of the respective locking-strips, and the parts will be held in this position by means of the engagement of pin 39 in slot 36. In this position of the parts the sashes may be moved freely up and down, the outer edge of each locking-hook lying parallel and flush with the respective sides of the parting-strip. To lock the sashes in any position to which they may be moved, it is only necessary to push plunger 38 inward, when the remainder of the operation will be automatic, the spring 22 raising the lever-arm 8 upward, and thereby, through the medium of rod 26, drawing the crank-arm 45 upward and spring 40 pressing the plunger 38 outward, bringing pin 39 again in slot 35.

It has herein been stated that the lever-arm 8 was slidably mounted on stud 11 and movable thereon against the resistance of leaf-spring 12 and that the edges of the sashes bore against the respective bearing-flanges 17 and 19, which are integral with said lever-arm 8. The purpose of this construction is to provide a yielding contact for the sashes whereby to offset any swelling or shrinkage of the latter, the construction described insuring that the said bearing-flanges will always remain in contact with the sashes, the lever-arm 8 moving on the stud 11 against or in obedience to the force of the spring 12, according as the sashes swell or shrink. By this movement of the lever-arm the locking-hooks will always be in position to engage in the apertures of the locking-strips.

Having thus fully described my invention, what I claim as new is—

1. In a sash-fastener, the combination with an upper and lower sash having on opposing side rails apertured locking-strips, of a lock seated in the window-sash frame at the meet-

ing-rails of said sashes said lock comprising a pivoted lever-arm having a vertically-extending locking-arm, locking-hooks extending from opposite sides of said locking-arm and adapted to engage in the apertures of the respective locking-strips, and means for operating said lever-arm, substantially as described.

2. In a sash-fastener, the combination with an upper and lower sash having on opposing side rails apertured locking-strips, of a lock seated in the window-sash frame at the meeting-rails of said sashes, said lock comprising a lock-casing having apertures therein, a pivoted lever-arm having a vertically-extending locking-arm bent at right angles to itself on opposite sides to project through the apertures in the casing, locking-hooks formed on said projecting portions and adapted to engage in the apertures of the respective locking-strips, and means for operating said lever-arm, substantially as described.

3. In a sash-fastener, the combination with an upper and lower sash having on opposing side rails apertured locking-strips, of a lock seated in the window-sash frame at the meeting-rails of said sashes, said lock comprising a lock-casing having apertures therein and provided with a stud, a lever-arm slidably and revolvably mounted on said stud and having a vertically-extending locking-arm bent at right angles to itself on opposite sides to project through the casing, a bearing-flange and a locking-hook formed on each projecting portion, said bearing-flanges adapted to bear against the edges of the sashes, respectively, and said locking-hooks to engage the apertures of the respective strips, a leaf-spring mounted on said stud and bearing at opposite ends against said locking-arm, and means for operating said lever-arm, substantially as described.

4. In a sash-fastener, the combination with an upper and lower sash, of a lock-casing seated in the sash-frame having apertures therein, and provided with a stud, a locking-arm slidably and revolvably mounted on the stud and having locking means adapted to engage with the respective sashes and bearing-flanges projecting through said apertures and bearing against the edges of the sashes, respectively, a leaf-spring secured on said stud and bearing on said locking-arm, and means for operating said locking-arm, substantially as described.

5. In a sash-fastener, the combination with an upper and lower sash having on opposing side rails apertured locking-strips, of a lock comprising a pivoted lever-arm having hooks adapted to be moved by said lever-arm into and out of engagement with the apertures in the respective locking-strips, and means for operating said lever-arm comprising a housing seated in the window-sash frame, a spring-pressed plunger revolvably mounted in said housing and having a crank-arm, a rod con-

necting the lever-arm and said crank-arm, stops carried by said housing, a pin carried by said plunger and adapted to engage said stops, whereby the plunger may be pushed in 70 against the resistance of the spring and be turned to operate, through the crank-arm and rod, said lever-arm, and on being released be thrown out by said spring to bring its pin into engagement with one of said stops, substantially as described.

6. In a sash-fastener, the combination with upper and lower sashes of a lock having locking-hooks adapted to engage said sashes, a lever-arm for operating said locking-hooks, a 80 spring operating to press said lever-arm upward to hold the locking-hooks in engagement with the sashes, and means for operating said lever-arm comprising a housing seated in the window-sash frame, a spring-pressed 85 plunger revolvably mounted in said housing and having a crank-arm, a rod extending from said lever-arm, an adjustable link connection between said rod and said crank-arm, stops carried by said housing, a pin carried by said 90 plunger and adapted to engage said stops, whereby the plunger may be pushed in against the resistance of its spring and be turned to operate, through the crank-arm, link and rod, said lever-arm, and on being released be thrown out by said spring to bring its pin into engagement with one of said stops, substantially as described.

7. In a sash-fastener, the combination with upper and lower sashes, of a lock having locking-hooks adapted to engage said sashes, a lever-arm for operating said locking-hooks, a spring operating to press said lever-arm upward to hold the locking-hooks in engagement with the sashes, and means for operating 100 said lever-arm comprising a cylindrical housing seated in the window-sash frame, a spring-pressed plunger revolvably mounted in said housing and projecting from each end thereof, a turn-button secured on one end of said plunger, the opposite end portion being squared, a crank-arm adjustably mounted on said squared portion, a rod extending from said lever-arm, a link connecting said rod and crank-arm, longitudinally-extending slots 105 formed in said housing, and connected by a cross-slot, a pin carried by said plunger and adapted to work in said slots, whereby the plunger may be pushed in against the resistance of its spring and be turned to operate, 110 through the crank-arm, link and rod, said lever-arm against the resistance of its spring, to unlock the fastener, and on being released be thrown out by the plunger-spring to bring said pin into engagement with one of said 115 slots; and whereby the parts may be automatically returned to a locked position by pressing said plunger inward, substantially as described.

8. In a sash-fastener, the combination with 120 an upper and lower sash and a parting-strip, of a lock-casing seated in the window-sash frame

4
at the meeting-rails of the sashes and inclos-
ing locking means for engaging said sashes,
said casing being cut away to form apertures
to receive said locking means, and having the
5 cut-away portions bent at right angles to the
casing, on opposite sides of a vertical line,
and seated in opposite sides of said parting-
strip, said parting-strip being cut out oppo-
site such bent-up portions to form recesses to

permit the movement of the locking means, to
substantially as described.

In testimony whereof I have hereunto set
my hand in presence of two subscribing wit-
nesses.

GEORGE R. MCCHESNEY.
